UNITED STATES PATENT OFFICE.

BENJAMIN DALTON MILLIKEN, OF SOMERVILLE, MASSACHUSETTS.

DESIGN FOR A TWINE-BOX.

SPECIFICATION forming part of Design No. 19,691, dated March 4, 1890.

Application filed February 3, 1890. Serial No. 339,100. Term of patent 3½ years.

To all whom it may concern:

Be it known that I, BENJAMIN DALTON MILLIKEN, a citizen of the United States, residing in Somerville, in the county of Middlesex and 5 State of Massachusetts, have invented and produced a new and original Design for Twine-Boxes, of which the following is a full, clear, and exact description, reference being had to the accompanying drawing, forming part of 10 this specification, in which is represented a perspective view of a twine-box constructed in accordance with my design.

The prominent features of my present design consist in a representation of a bottle 15 of a square or rectangular shape in cross-section for the body of a carriage on wheels, with the figure of a driver and a pair of horses, the said design being adopted by me for a twine-box for store service, &c.

A is the floor or bottom of a dray or carriage, resting on an axle provided with a pair of wheels B B.

C is a representation of a bottle of square or rectangular form in cross-section located on the carriage-floor.

D is a projecting front with a recess formed therein for sheltering the driver F. G G are a pair of horses.

What I claim is—

The design for a twine-box, as herein shown 30 and described.

Witness my hand this 3d day of January, 1890.

BENJAMIN DALTON MILLIKEN.

In presence of—

N. W. STEARNS,
GRACE B. FRASER.
